US00D958685S

(12) United States Design Patent (10) Patent No.: US D958,685 S
(45) Date of Patent: * Jul. 26, 2022

(54) NECKLACE

(71) Applicant: Harry Winston SA, Plan-les-Ouates (CH)

(72) Inventor: Rie Yatsugi-Kang, New York, NY (US)

(73) Assignee: Harry Winston SA, Plan-les-Ouates (CH)

() Term: 15 Years

(21) Appl. No.: 29/748,431

(22) Filed: Aug. 28, 2020

(30) Foreign Application Priority Data

Mar. 3, 2020 (WO) WIPO92715

(51) LOC (13) Cl. 11-01

(52) U.S. Cl.

USPC D11/7

(58) Field of Classification Search

USPC D11/6-8, 10, 11, 16, 3

CPC A44C 13/00; A44C 15/00; A44C 15/005;

A44C 25/001

See application file for complete search history.
